UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

1,419,182.

Specification of Letters Patent. Patented June 13, 1922.

Original application filed November 27, 1917, Serial No. 204,157. Divided and this application filed April 20, 1920. Serial No. 375,201.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention is a division of my application No. 204,157, filed November 27, 1917, (now Patent No. 1,340,864, dated May 18, 1920) and relates principally to the class of typewriting machines in which a single platen may co-operate with two sets of systems of types, whereby, when typewriting a page in one language, some of the words may be typewritten in a foreign language, or whereby some words may be typewritten in italic among others written in roman. It has been proposed to place one type-system by the side of another, and to displace the platen from side to side of the machine, to position to co-operate with either type-system; each type-system having a separate keyboard.

One of the objects of the present invention is to avoid the necessity of displacing the platen from one side of the machine to the other, and to avoid the bulky dimensions that are necessary where one type-system is placed by the side of another, and further to avoid the necessity for the operator to shift his hands from one keyboard to another.

To these ends, I arrange the types of both type-systems to strike all at one printing point, so that the platen need never be displaced endwise for bringing it into co-operation with one or the other sets of type-bars, but its travel may be confined within the range usual in machines having but a single system of type-bars. The type-bars of one system preferably alternate with those of the other system, and each key is preferably connected to two type-bars, one in each system, and means are provided, preferably controlled by a style-shift-key in the keyboard, for selecting the system to be operated.

In each system of type-bars there are provided both upper and lower-case types, and

case-shifting mechanism is employed in each system, for bringing either capital types or lower-case types into use.

In order to condense all of the type-bars in both systems within such limits as to avoid the necessity of making the type-bars unduly long, I employ relatively long type-bars for one system and relatively short type-bars for another system, the short type-bars alternating with the long type-bars. Each type-bar carries upper and lower-case types, and for compactness the types on the short type-bars (which lie between the shanks of the long type-bars), are made to shift radially, so that the shifting movement of each type is in a direction lengthwise of the bar, and hence none of these radially-shifting types needs to project very far laterally from its type-bar, and hence may lie compactly between the shanks of the adjacent long type-bars.

The selection between sets of type-bars to be used is made by having each pair of type-bars, one in each set, operated by a floating lever, which, in turn, is operated by a character key. Each floating lever may have alternative fulcrums, so that when a lever fulcrums at one end, one of the connected pair of type-bars is actuated, and when it fulcrums at the other end, the other of the pair of type-bars is actuated. The fulcrums for the two series of type-bars and their common floating levers may consist in a pair of plates or circular combs, having a series of spaced teeth, which form alternate ridges or obstructions and slots. The ridges or teeth on one plate are radially opposite the slots on the other plate. Thus, the floating levers may engage all fulcrums on one plate or the other according to whether the ridges or slots of that plate are in register with the floating levers. The two plates are united, to form a segment, so as to move as a unit, and thus bring either the slots or ridges of one plate or the other in register with the floating levers. If the slots of one plate are brought in register with a series of floating levers, the fulcrum ridges of the other plate will at the same time be brought into register therewith. In this way, the fulcrum of each floating lever is alternatively

either on one side or the other side of the point of connection of the operating type-key connected thereto, whereby either the type-bar of one set or the type-bar of the other set will be operated. The position of the segment may be changed by a shift-key, to give the selection between the two sets of type-bars.

For the selection of the types of the short type-bars, the type-heads thereon have a normal position corresponding to the printing of one set of types thereon, and an abnormal position corresponding to the printing of the other set of types; the abnormal position being determined by a rail which shifts each type-head as the type-bar moves up to print.

Platen-shifting mechanism is provided in combination with the long set of type-bars, which have their type-blocks rigidly secured thereto and set at various angles of the type-bars as in the Underwood standard typewriter. The platen-shifting mechanism comprises a case-shift key which may be connected to operate the type-shifting mechanism for causing the type-blocks of the short bars to be shifted radially. Either one of two sets of types may be selected by a style-shift or selecting key. Either one of the case-shifting mechanisms is connectible by the style-shift-key to the case-shift key. Thus, with this arrangement, there is provided a case-shift-key which may actuate either one of two case-shift-mechanisms, the effectiveness of the case-shift-key being under the control of the style-shift-key.

From the foregoing, it will be understood that the same keyboard may be rendered effective, by means of a key, to bring the types of either set to the printing point, and that by suitable mechanism, operated by another key, the types in either set may be caused to print either upper-case or lower-case letters.

Other features and advantages will hereinafter appear.

In the accompanying drawings,

Figure 1 is a vertical section, taken from front to rear, with parts omitted to simplify the showing. In this view, the machine is in a condition to print small, vertical characters corresponding to a fulcruming of the upper ends of the floating levers, and thus the use of the long set of type-bars and the rear set of types thereon.

Figure 2 is a front view in elevation, partly broken away to show the underlying structure, and showing the fulcrum segments in their normal positions in which the long set of type-bars is effective.

Figure 3 is a detail view, in front elevation, of the fulcrum segments, showing them connected as a unit and in their shifted position; the style-shift-key is, therefore, in its depressed position.

Figure 4 is a horizontal view of part of

one of the short type-bars, with the type-head broken away to show the pivotal connection thereof to the type-bar and the means of yieldingly locking the type-head in either of its adjusted positions.

Figure 5 is a view of the parts shown in Figure 4, except that it is not broken away. This view illustrates one of the type-bars off to one side.

Considering more particularly the separate parts of the invention, character keys 1 depress key-levers 2 to rock same about an intermediate pivot 3. Each key-lever is connected to rock a bell-crank 4, about a fulcrum 4^a intermediate the ends thereof, to swing a floating lever 5, pivoted at 5^a to the upper end of the bell-crank 4. These upper ends of the bell-cranks 4 are bent so as to lie in radial planes which intersect at the printing point. This is done so that the floating levers may be radially disposed in substantially the same planes with the links 6 and 7 and type-bars 8 and 9, to which the links are connected. There are two sets of type-bars 8 and 9, the type-bars of one set being alternately placed between those of the other set, and both sets are supported on suitable segments 8^a and 9^a, respectively, which may be of any well-known construction. When a type-bar of either set is operated, it is swung up rearwardly to cause roman style of types, indicated generally at 10, or italic style of types, indicated generally at 10^a, depending upon the set to which the type-bar belongs, to strike the platen 11, which may be mounted to rotate on a carriage of any well-known character.

The sets of type-bars 8 and 9, as above stated, are provided with different styles of types 10 (roman) and 10^a (italic), respectively. To selectively render either the roman types 10 or italic types 10^a effective, or, in other words, to determine which set of type-bars 8 and 9 shall be in use at any particular time, there is provided a style-shift-key 80, which, when depressed, rocks a shift-lever 81 about the pivot 3, so as to rock a bell-crank 15 (Figures 1 and 2), having a pin-and-slot connection 16 with a pair of fulcrum plates 17 and 18. The fulcrum plates 17 and 18 may be curved and are connected by strips 19 to form a segment 20 to move so that the fulcrum plates 17 and 18 may move as a unit. The segment 20 is supported for easy movement by means of rollers 21 on a suitable support. The rollers engage in grooves 21^a, provided in the segment. The segment 20 has a normal position, illustrated in Figure 2, and is moved against the tension of a spring 22, by the key 80, to the Figure 3 position. The limits of movement of the segment are determined by a pin 23, which extends between two stops 24 and 24^a, having enough space between them to allow the required amount of shifting of the seg-

ment. It should be understood that other means for limiting the movement of the segment 20 may be used.

The purpose of the plates 17 and 18 is to form alternative fulcrums for the lower and upper ends of the floating levers 5. The alteration of the fulcrums is obtained by having the plates of the segment formed after the manner of combs with teeth or ridges 25 separated by slots 26. The ridges of the lower fulcrum plate 17 are radially opposite the slots of the upper fulcrum plate 18, and vice versa. The type-actions and thus the floating levers are radially disposed about a common center. This causes the plates 17 and 18 to either act as fulcrums for the lower ends of the floating levers 5 or for the upper ends of the floating levers 5, according to the adjustment of the segment 20.

Normally, the roman types 10 are effective and the segment 20 is in the position of Figures 1 and 2, with the ridges or teeth of the upper plate 18 in register with the levers 5. Under these conditions, when one of the character keys 1 is depressed to rock the bell-crank 4, the bell-crank will tend to draw the associated floating lever 5 rearwardly. The upper end thereof, however, will be blocked against movement by one of the ridges or obstructions 25 and the lower end will enter one of the slots 26, thereby drawing on the link 6 and thus swinging a type-bar 8 up against the platen 11. The slots 26 are preferably long so as to guide the lever 5 in its movement.

Type-blocks 61 are rigidly secured to the long type-bars 8 and are set on the type-bars at such an angle relative to the shanks 40 of the type-bars, as in the Underwood standard typewriter, so that the types 61 will strike the platen 11 vertically. In combination with this set of types 61, I have shown case-shifting-mechanism, preferably a 45 platen-shift comprising a case-shift-key 62, which, when depressed, swings a lever 63 about a pivot 64 to cause a pin 65 controlled by said lever to swing a lever 66 about its pivot 67 and pull downwardly on a link 50 68, which may be guided so as to have a roller 69 at its upper end overlie a cross-bar 70 to move the latter downwardly and shift the platen 11 from lower to upper-case position. The cross-bar 70 is supported at its 55 ends by two arms 71 extending rearwardly from a rock shaft 72 supported for swinging movements on a typewriter carriage 73, which may be guided to travel crosswise of the machine in any well-known manner. 60 The rock shaft 72 is provided with forwardly-extending arms 74, which, when the platen is being shifted from lower to upper-case position, swing upwardly to raise a platen frame 75 carrying the platen 11. To 65 assist in guiding the platen-frame during

case-shifting movements of the platen 11, parallel links 76 are provided.

I have provided automatically-actuated means for connecting either the platen-shifting mechanism for the types on the long 70 type-bars or the type-block-shifting mechanism hereinafter described for the short type-bars to the shift-key 62, which is preferably controlled by the style-shift-key 80. This is done when the segment 20 is shifted 75 for type-bar-selecting. For this purpose, the style-selecting-lever 81 is provided with a downwardly-projecting arm 82 engaging with a pin 83, to slide a bar 84, guided in its movement and supported on the case-shift-lever 63 by studs 85, to move the slide-bar rearwardly, thereby causing a disengagement of the pin 65 with the lever 66, thus disconnecting the platen-shifting-mechanism from the case-shift-key 62. At the 85 same time, a hook 77 is moved into engagement with a bent-off portion 78 of a link 79, to connect the case-shift-mechanism for the type-blocks or type-heads 27, hereinafter described, with the case-shift-key. The link 90 79 may be guided in any suitable manner, so as to maintain the connection with the hook 77 during the actuation of the latter. Suitable locking levers 54 and 56, as indicated in Figure 1, may be provided to hold the 95 case-shift-key 62 and the style-shift-key 80 in their actuated positions. Suitable stops may also be provided to limit the movements of said keys.

When the italic types 10^a are effective, 100 the slots in the upper plate 18 are in register with the upper ends of the levers 5, while the teeth or ridges of the lower plates 17 are in register with the lower ends of the floating levers 5. Thus, when one of the 105 character keys 1 is depressed, the lower end of the corresponding floating lever is obstructed in its movement, so that the link 7 is drawn on to operate one of the type-bars 9 of the top set to cause italic types 10^a to 110 strike the platen 11.

Each short type-bar 9 which may be operated, as above described, has a swinging type-head 27 with the types 10^a thereon and which is pivoted to the type-bar at 28. Each 115 type-head is normally locked in the position shown in Figures 1 and 4, by a spring detent 29 to yieldingly engage in sockets 30, of which there are two, provided in the type-head. Each type-head can be swung around 120 its pivot until the detent 29 enters the other socket 30 to yieldingly lock the type-head in its shifted position. In the position of Figure 1, the lower-case type is used. Normally, that is to say, before case-shifting 125 operations, either one of the type-bars 8 and 9 may be operated to print with lower-case type, as indicated in Figure 1, by rendering either set of type-bars effective with the style-shift-key 80.

To perform case-shifting operations, for the types 10^a on the small bars 9, the small bars having been previously selected, the key 62 is depressed to swing the key-lever 63 about its pivot 64 to draw down on the link 79 which is engaged by the hook 77, so as to rock an arm 36 downwardly against the tension of a spring 35. The arm 36 is secured to a shaft 37, so as to rock the same, thereby moving a lever 38, secured thereto, to thrust rearwardly on a link 39. The link 39 is operated so as to have a substantially parallel movement by means of a second lever 40 extending upwardly from a rock-shaft 40^a and connected by a link 41 to the lever 38. The link 39 shifts a curved, obstructing or camming rail 43, thereby rendering the case-shifting means for the small bars effective. To maintain the camming rail 43 in its movement substantially parallel to itself, there is provided, in addition to the link 39, links 44 and 45 at the ends of the rail 43 to support and guide the rail when moved. Bell-crank 46 and 47 move the links 44 and 45, to which they are respectively connected. The latter, in turn, are operated by links 48 and 49 connected respectively to the arm 36 and a similar arm 50 secured to the rock shaft 37. The links 44 and 45 are additionally supported and guided in their movement by pivoted arms 51.

The rail 43 underlies the outer ends of lugs 52 of the type-heads 27. When the case-shift-key 62 is operated, however, the rail is moved rearward into the paths of cams 52^a on the type-blocks 27, but does not change the position of the type-heads 27 until a type-bar is actually operated. When a type-bar is operated, the rail 43 is engaged by the heel or cam 52^a of type-head 27, and rocks the type-head about its pivot 28 to bring the upper-case character into use. When the type-head leaves the rail 43, it is held in its shifted position by the detent 29 and swings up to the platen 11, so as to cause the upper-case type thereon to strike the platen. When the type-bar swings back from the platen to its normal inactive position, the type-head 27 is automatically rocked back to its lower-case position by the lug 52 engaging with the rail 43.

A suitable type-bar-rest 53 is provided, which supports the forward ends of the type-bars 8 and 9 in their normal positions, as indicated in Figure 1. It will be seen by an inspection of Figure 1 that the lugs 52 are normally out of engagement with the obstructing bar 43. This slight clearance may be caused by the detents 29, the pointed ends of which position the type-blocks 27 relatively to the type-bars and move each type-block slightly after the latter has returned to its normal position, thereby raising the lug 52 out of engagement with the associated obstructing bar 43. This is done to avoid any unnecessary friction when the obstructing

bar 43 is moved during a case-shifting operation.

It will be understood that each set of type-bars is provided with a complete set of alphabetical types and that other characters including numerals may also be included on the type-blocks of each set of types. 70

Variations may be resorted to within the scope of the invention, and portions of the improvements may be used without others. 75

Having thus described my invention, I claim:

1. The combination with a platen, of type-bars, two independently-actuable case-shift mechanisms, a case-shift key, and means for rendering either one of said case-shift mechanisms under the control of said case-shift key. 80

2. The combination with a platen, of type-bars, a plurality of complete sets of alphabet types on said type-bars, all of said types having a common printing point and co-operating with said platen, each set of types having independently-actuable case-shifting mechanism, and means, including a single key, for actuating any one of said case-shifting mechanisms. 85 90

3. The combination with a platen, of type-bars, a plurality of complete sets of alphabet types having a common printing point, and co-operating with said platen, each set of types having independently-actuable case-shifting mechanism, a single key for actuating any one of said case-shifting mechanisms, and means for rendering any one of said case-shifting mechanisms under the control of the case-shift key. 100

4. The combination with a platen, of type-bars, a plurality of complete sets of alphabet types on said type-bars, all of said types co-operating with said platen and having a common printing point, platen case-shifting means for one of said sets of types, and type case-shifting means for another of said sets of types. 105

5. The combination with a platen, of type-bars, a plurality of complete sets of alphabet types on said type-bars, all of said types co-operating with said platen and having a common printing point, platen case-shifting means for one set of types, means for effecting a radial case-shifting of the types of the other set, and a single key for actuating any one of said case-shifting means. 115

6. The combination with a platen, of type-bars, a plurality of complete sets of alphabet types on said type-bars, all of said types having a common printing point, and co-operating with said platen, platen case-shifting means for one set of types, type case-shifting means for effecting a radial shifting of the types of the other set, a single key for actuating any one of said shifting means, and a key for selecting either set of types, said key being effective to render 120 125 130

either one of said shifting means under the control of said first-mentioned key.

7. The combination with a platen, of a set of long type-bars and a set of short type-bars, each set of type-bars having a complete set of alphabet types, all of the types having a common printing point, platen-shifting mechanism for the types on the long type-bars, type-block shifting mechanism 10 for the types on the short type-bars, a set of alphabet keys, and means whereby said keys may be made effective at will on one of said sets of type-bars and the corresponding case-shift mechanism rendered effective.
- 15 8. The combination with a platen, of two sets of type-bars, each set having a complete set of alphabet types thereon, all of the types having a common printing point, and case-shift means including a platen-shift effective 20 only when one of said sets of type-bars is effective.

9. The combination with a platen, of a plurality of sets of type-bars, one of said sets having long type-bars, one of said sets 25 having short type-bars, each set of type-bars having a complete set of upper and lower-case alphabet types, platen-shifting mechanism for the types on said long type-bars, and type-shifting mechanism for the 30 types on said short type-bars.

10. The combination with a platen, of type-bars, a plurality of complete sets of alphabet types on said type-bars, all of said type-bars having a common printing point, 35 platen-shifting means for one set of types, type-shifting means for one set of types, a key-lever, and a slide whereby said key-lever may be connected with either of said shifting means.

11. The combination with a platen, of 40 type-bars, a plurality of complete sets of alphabet types on said type-bars, all of said types having a common printing point, platen-shifting means for one set of types, type-shifting means for one set of types, a 45 key-lever, a connecting member which may be moved to positions to connect said key-lever with either of said shifting means, a set of alphabet keys, and means for rendering said alphabet keys effective on the type-bars of either one of said sets of alphabet types and concomitantly moving said connecting member to render said key-lever effective on either said platen-shifting means 50 or said type-shifting means in accordance 55 with the set of types to be used.

12. The combination with a platen, of type-bars, a plurality of complete sets of alphabet types on said type-bars, all of said types having a common printing point, 60 platen-shifting means for one set of types, type-shifting means for one set of types, a key-lever, and a member adapted to connect said key-lever to either of said shifting means mounted on said bar. 65

13. The combination with a platen, of a plurality of sets of type-bars, each set of type-bars having a complete set of upper and lower-case types, all of the types having a common printing point, platen-shift- 70 ing mechanism for the types on one set of type-bars, and type-shifting mechanism for the types on another set of type-bars.

JOHN WALDHEIM.
